United States Patent Office

Des. 185,442
Patented June 9, 1959

185,442

CLOCK OR SIMILAR ARTICLE

Monte L. Levin, Roslyn Heights, N.Y., assignor to General Electric Company, a corporation of New York

Application February 21, 1958, Serial No. 49,734

Term of patent 14 years

(Cl. D42—7

FIG. 1

Des. 185,442

PAGE 2

Fig. 2.

Fig. 3.

Des. 185,442

PAGE 3

FIG. 4.

FIG. 5.

Fig. 6.

Fig. 1 is a front perspective view of a clock embodying my new design;

Fig. 2 is a front elevational view;

Fig. 3 is a top plan view of the clock shown in Fig. 1;

Fig. 4 is a bottom plan view of the clock shown in Fig. 1; and

Fig. 5 is a side elevational view of the clock shown in Fig. 1.

Fig. 6 is a cross-sectional view taken along line 6—6 of Fig. 3.

The ornamentation partially shown in Figs. 1, 2 and 5 is understood to continue over the complete surface of the innermost face.

I claim:

The ornamental design for a clock or similar article, substantially as shown and described.
